DESIGN FOR A GAUGE FOR AUTOMOBILE BRAKE DRUMS OR SIMILAR ARTICLES

Charles W. Bauberger and Edward T. Liess,
Malverne, N. Y.

Application December 21, 1938, Serial No. 81,914

Term of patent 14 years

To all whom it may concern:

Be it known that we, Charles W. Bauberger and Edward T. Liess, citizens of the United States, both residing in Malverne, Long Island, county of Nassau and State of New York, have invented a new, original, and ornamental Design for a Gauge for Automobile Brake Drums or Similar Articles, of which the following is a specification, reference being had to the accompanying drawing, forming part thereof.

Fig. 1 is a perspective view of a gauge for auto-

mobile brake drums or similar articles, embodying our invention.

Fig. 2 is a cross sectional view thereof, on the plane of the line 2—2 of Fig. 1.

We claim:

The ornamental design for a gauge for automobile brake drums or similar articles, substantially as shown.

CHARLES W. BAUBERGER.
EDWARD T. LIESS.
